TABLE

Bert J. Klein and Andre Bus, Altavista, and John B. Thorn, Lynchburg, Va.

Filed Apr. 19, 1965, Ser. No. 84,868

Term of patent 14 years

(Cl. D33—14)

The end of the article not shown is like the end shown and the back of the article is also like the front shown.

We claim:

The ornamental design for a table, as shown and described.
